RELISH DISH OR SIMILAR ARTICLE

John Lewis Woodland, Moorestown, N. J., assignor to Fisher, Bruce & Company, Philadelphia, Pa., a corporation of Pennsylvania

Application July 1, 1958, Serial No. 51,620

Term of patent 7 years

(Cl. D44—15)

Figure 1 is a top plan view of a relish dish or similar article showing my new design;

I claim:

The ornamental design for a relish dish or similar article, as shown.
